188,708

WATER SKI SCOOTER

Richard Vogt, Santa Barbara, Calif., assignor to Curtiss-Wright Corporation, a corporation of Delaware

Filed May 29, 1959, Ser. No. 56,135

Term of patent 3½ years

(Cl. D71—1)

FIG. 1.

FIG. 2.

FIG. 3.

FIG. 4.

FIG. 5

I claim:

The ornamental design for a water ski scooter, substantially as shown.
